UNITED STATES PATENT OFFICE

JOHN HAYEN, OF MILLEDGEVILLE, ILLINOIS

SNOW REMOVING APPARATUS

Application filed January 27, 1931. Serial No. 511,611.

The present invention relates to an apparatus for removing snow from the street, roadways and the like and has for its prime object to provide an apparatus which is compact in its arrangement of parts and is capable of being mounted on the front of a truck, tractor, locomotive and the like.

Another very important object of the invention resides in the provision of an apparatus of this nature which will suck up the snow from the street or the like and blow the same out into a suitable receptacle such as a truck or the like to be hauled away.

A still further very important object of the invention resides in the provision of an apparatus of this nature which is exceedingly simple in its construction, comparatively inexpensive of manufacture, strong and durable, thoroughly efficient and reliable in use and operation and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawings:

Figure 1 is a top plan view of an apparatus embodying the features of my invention.

Figure 2 is a side elevation thereof.

Figure 3 is a vertical longitudinal section therethrough.

Figure 4 is a vertical transverse section taken substantially on the line 4-4 of Figure 3.

Figure 5 is a front elevation of the apparatus.

Figure 6 is a detail section taken through the connection between the elbow 34 and the conduit 31.

Figure 7 is a sectional view taken substantially on the line 7-7 of Figure 3.

Figure 8 is a sectional view taken substantially on the line 8-8 of Figure 7.

Figure 9 is a sectional view taken substantially on the line 9-9 of Figure 3, and

Figure 10 is a sectional view through the beater.

50 Referring to the drawings in detail it will

be seen that a frame F comprises side members 5 in spaced coextensive parallelism merging at their rear ends into inwardly directed extensions 6 which in turn merge into rearwardly directed extensions 7 adapted to be fastened in any suitable manner on the chassis of a truck or any other mobile apparatus so that the frame is located forwardly thereof.

A cross member 8 is secured to the members 5. A circular casing 9 is mounted in the frame between the side members 5 by suitable brackets 10 or other equivalent means and has a shaft 11 rotatable therein with blades 12 radiating outwardly therefrom. This shaft 11 is journalled through a bearing 14 on the cross member 8. A longitudinal member 15 extends between the cross member 8 and the front end of the truck chassis which is denoted by numeral 16. A bearing 17 is mounted on this member 15 and similar bearings 17' are mounted on the side members 5 in alignment with the bearings 17 and a shaft 18 is journalled through these bearings 17 and 17' terminating to the outer sides of the side members 5.

Gearing 19 connects the shaft 11 with the shaft 18. A shaft 20 is journalled through a bearing 21 on one of the extensions 7 and is operatively connected in any suitable manner with the engine of the truck in a manner not shown as this is not of the essence of the invention. Pulley and belt means 22 operatively connect shaft 20 with the shaft 18. Numeral 24 denotes a hollow transversely elongated shoe open at its bottom end and tapering upwardly and merging into a conduit 25 communicating with the front center of the casing 9 through an opening 26. A rectangular skirt 27 is telescoped over the shoe 24 and has vertical slots 28 to receive bolts 29 in the shoe 24 and these bolts may be loosened and the skirt adjusted to terminate the proper distance from the ground depending upon the depth of the snow and then the bolts tightened to hold the skirt in this desired adjusted position. A tangentially disposed outlet neck 30 rises from one side of the casing and a conduit 31 has a curved end 32 swiveled on the neck 30 as at 100

33. An elbow 34 is fixed as at 35 on the outer end of the conduit 31. This conduit 31 is swung and controlled by a link rod 36 connected with a lever 37 conveniently mounted 5 on the truck.

Arms 39 have ends rockable on the ends of the shaft 18 and extend forwardly. A rod 40 is connected to intermediate portions of these arms 39. A beater B is journaled be- 10 tween the forward ends of the arms 39. This beater comprises a shaft 41 with the ends journaled in the forward ends of the arms 39, a drum 42 mounted on end disks 43 fixed on the shaft 41 and a central wheel 44. A plurality 15 of teeth 45 radiate outwardly from the drum.

A chain and sprocket connection 46 is provided between the shaft 18 and the shaft 41. A rocker shaft 48 is journaled in bearings 49 on the forward ends of the side members 5 and 20 has cranks 50 and 51 thereon, the latter being a bell crank.

Links 52 connect the cranks 50 and 51 with the cross rod 40. A link 53 is connected with the bell crank 51 and with a lever 55 mounted 25 conveniently on the truck and having a detent 56 and a rack segment 57 associated therewith so that the lever 55 may be rocked to raise and lower the beater with respect to the ground.

The operation of the apparatus is quite 30 simple. After the beater, the skirt, and the outlet pipe 31 have been adjusted as desired, the rotation of the beater beats up the snow so that the same will be in proper condition to be sucked up through the shoe into 35 the casing and exhausted out through the neck 30 and pipe 31 into a truck or the like.

It is thought that the construction, operation, utility and advantages of this invention 40 will now be quite apparent to those skilled in this art without a more detailed description thereof.

The present embodiment of the invention has been described in considerable detail merely for the purposes of exemplification 45 since in actual practice it attains the features of advantage enumerated as desirable in the statement of the invention and the above description.

It will be apparent that changes in the de- 50 tails of construction, and in the combination and arrangement of parts may be resorted to without departing from the spirit or scope of the invention hereinafter claimed or sacrificing any of its advantages.

55 Having thus described my invention, what I claim as new is:

1. In an apparatus of the class described, a frame, a casing in the frame, a shaft journaled in the casing and having blades ra- 60 diating therefrom in the casing, a hollow shoe open at the bottom and merging into a conduit connected with the center of the casing, and a tangentially disposed outlet neck rising from one side of the casing, a 65 pair of arms rockably mounted on the frame

to the rear of the casing and extended forwardly of the casing, a shaft journaled between the forward ends of the arm, a beater on the shaft, means for rotating the beater, a rocker shaft across the frame in front of the casing, cranks on the shaft, links connecting the cranks with the arms, and means for rocking the rocker shaft to raise or lower the beater. 70

2. A snow removing device comprising a frame, a blower supported by the frame, a laterally extending shoe having its lower end open, a conduit connecting the top of the shoe with the center of the blower, a beater device supported in front of the shoe for agitating the snow before it is picked up by the suction in the shoe and an adjustable outlet for the blower. 80

In testimony whereof I affix my signature.

JOHN HAYEN. 85
